SHIRT NECKBAND

Edmund B. Sullivan, Mount Vernon, N. Y.

Application April 24, 1939, Serial No. 269,614

1 Claim. (Cl. 2—127)

This invention relates generally to outer shirts having neckbands provided with pockets for the insertion of collar buttons, but more specifically to means for separating the walls of the pocket of the neckband after same have been starched together following laundering, whereby the base of a collar button may be inserted within the said pocket.

The main object of the invention resides in the provision of a neck band having a pocket formed therein to house the base of a collar button, the said pocket having a tab member secured intermediate the width of the pocket whereby the outer wall may be separated from the inner wall for insertion of said collar button.

Another object of the invention resides in the provision of a neckband having a pocket formed therefrom intermediate the width of which a tab member is secured to the inner surface of the outer wall by means of lines of stitching whereby the pocket member walls are easily separated after having been secured together by starch in the laundering process.

These objects and other incidental ends and advantages of the invention will hereinafter appear in the progress of the disclosure and as pointed out in the appended claim.

Accompanying this specification is a drawing showing a preferred form of the invention wherein corresponding reference characters designate corresponding parts throughout the views and wherein:

Figure 1 is a perspective view of a shirt showing a tab member attached to the neckband.

Figure 2 is a sectional view of Figure 1 along the plane 2—2 thereof.

Figure 3 is a view similar to Figure 2 except that the pocket member is shown opened.

Figure 4 is a sectional view of the neckband of a shirt not provided with a tab member.

In accordance with the invention and a preferred embodiment shown in the accompanying drawing, numeral 10 indicates a shirt having a neckband generally designated by numeral 11. Customary button holes 12 and 13 are provided on the neckband 11.

The neckband 11 is preferably comprised of inner and outer walls 14 and 15, and as shown in the drawing is formed by folding the neckband material over on itself, the fold constituting the upper edges of the neckband. The lower edges of walls 14 and 15 are secured to the shirt edge 10' by means of a line of stitching 16 which latter is interrupted between two spaced and transverse lines of stitching 17 and 18 laterally

of button hole 13 and forming the inner and outer walls 14 and 15. Another line of stitching 16' is provided between the lower edge of inner wall 14 situated between the spaced transverse lines of stitching 17 and 18 and the shirt edge 10'. Thus, a channel 19 is formed between the walls 14 and 15 of the neckband except for that portion between lines of stitching 17 and 18 which portion forms a pocket 20 with the lower edge of wall portion 15 free.

A tab member 21 is adapted to be secured within pocket 20, lateral edges of the said tab member 21 being disposed preferably inwardly of the lines of stitching 17 and 18 whereby it becomes possible to secure the said tab member to the outer wall 15 by distending the latter from the inner wall. Thus, the tab member 21 is preferably secured to outer wall 15 of the pocket by lateral lines of stitching 22 and 23 and also, if desired, by an upper line of stitching 24 as shown in Figure 3. The aforementioned button hole 13 is adapted to register with a corresponding button hole 25 in the tab member 21 whereby the base of a collar button 26 may be used against the outer surface of inner wall 14 and projected through hole 25 of tab 21 and hole 13 in the outer wall 15 of the pocket member. The tab 21 preferably projects below the base of neckband 11 as shown in Figure 1. By pulling on the projecting portion of tab 21, it is easily seen how the outer wall 15 of pocket 20 is separated from the inner wall 14. This separation is made more easy both from the standpoint of manufacture as has been above mentioned and from the standpoint of performance by making the width of tab 21 narrower than the width of the pocket 20.

In Figure 4, a neckband is shown affixed to a shirt 10' wherein a channel 19' is formed between inner and outer walls 14' and 15', the said neckband not being provided with a tab member. Such a neckband may easily be converted into a neckband shown in Figures 1, 2 and 3 by forming a pocket therein by the expedient of providing two spaced transverse lines of stitching similar to lines of stitching 17 and 18 and securing to the outer wall a fabric piece, thus forming a tab member in accordance with the prior description.

I wish it distinctly understood that the tab member as applied to a pocket in the rear of the neckband, may also be applied to a pocket at the front of the neckband to accommodate a front collar button.

I wish it understood that minor changes and

variations in the integration, location and material of the parts may all be resorted to without departing from the spirit of the invention and without departing from the scope of the appended claim.

I claim:

In a shirt of the class described in combination, a neckband having walls forming a closed channel therebetween, the said channel having a portion provided with an opening at the lower 10 edge for the insertion of a collar button and be-

ing provided with spaced transverse lines of stitching joining the walls together to form a pocket, the outer wall of said pocket being provided with a button hole, a tab member having a button hole within the said pocket to register with the button hole of the outer wall of the pocket, the tab member being secured to the outer wall of the pocket at least at the lateral edges thereof and across the height thereof.

EDMUND B. SULLIVAN.
